UNITED STATES PATENT OFFICE

2,587,440

STORM BLIND

Van H. Burkhart, La Marque, Tex.

Application November 4, 1948, Serial No. 58,191

1 Claim. (Cl. 189—63)

1

This invention relates to storm blinds, and the primary object of the invention is to provide a device of this kind including a pair of blind stops in the form of longitudinally grooved guides, and a plurality of separate superimposed slats having their ends slidably engaged in the grooves of said guides, said guides having sections at their lower ends which are removable to permit ready successive insertion or removal of the slats with respect to said guides from the inside of a building having a window equipped with the blind.

A further object of the invention is to provide a blind of the above kind in which the slats have coacting lateral end flanges to support them one upon another in outwardly inclined louver fashion to afford ventilation.

The exact nature of the present invention, as well as other objects and features thereof, will become apparent from the following description when considered in connection with the accompanying drawings, in which:

Figure 1 is a vertical sectional view, partly broken away, of a window equipped with a storm blind constructed in accordance with the present invention;

Figure 2 is an enlarged fragmentary horizontal section, partly broken away, taken on the line 2—2 of Figure 1;

Figure 3 is a fragmentary vertical section taken on the line 3—3 of Figure 1.

Referring in detail to the drawing, 5 indicates a window frame including a sill 6, a head jamb 7, side jambs 8, special blind stops 9, inner stops 10, and parting strips 11. Vertically slidably upper and lower sashes 12 and 13 are mounted between the stops 9 and strips 11 and between the stops 10 and strips 11, as usual.

In accordance with the present invention, the blind stops 9 comprise longitudinally grooved guides, and a plurality of separate superimposed slats 14 have their ends slidably engaged in the grooves of said guides, said guides having sections 15 at their lower ends which are removable to permit ready successive insertion or removal of the slats relative to the guides from the inside of the building having the window, upon raising the lower sash 13. Thus, should a screen be mounted in the window frame at the outer sides of the blind stops, it need not be removed to allow insertion or removal of the slats.

It will be noted that the grooves of the guides 9 are wider than the thickness of the slats so that the latter may be disposed in outwardly inclined louver fashion, and said slats have coacting lateral end flanges 16 to support them one upon another in such louver fashion to afford ventilation.

The stops or guides 9 are preferably in the

2

form of sheet metal channels having inwardly directed angular flanges 17 and 18 on the sides thereof, the adjacent portions of said flanges being disposed in spaced parallel relation to form the grooves therebetween which receive the ends of the slats. The removable sections 15 comprise portions of the inner sides and inner flanges 18 of the guides, and are secured in place by suitable means, such as screws 19. Other screws 20 may secure the major portions of the guides in place.

In use, the sections 15 are removed, and the slats are inserted in the guides singly at the lower ends of the latter, the slats being pushed upwardly until the complete blind is formed. By reversing this operation, the slats may be removed.

From the foregoing description, it is believed that the construction, manner of use and advantages of the present invention will be readily understood and appreciated by those skilled in the art. It will be apparent that the blind is simple in construction, easy to install and convenient to use. Modifications and changes in details of construction are contemplated, such as fairly fall within the spirit and scope of the invention as claimed.

Having described the invention, what is claimed as new is:

30 A storm blind for windows comprising longitudinally grooved guides, and a plurality of separate superimposed louver slats having their ends slidably engaged in the grooves of said guides, said guides having removable inner sections at their lower ends adapted to be removed to permit successive insertion or removal of the slats relative to said guides from the inner side of the window, said guides comprising sheet metal channels having inwardly directed angular flanges on the sides thereof, the adjacent portions of said flanges being disposed in spaced parallel relation to form the grooves therebetween which receive the ends of the slats, the removable sections comprising portions of the inner sides and the inner flanges of the guides, and means to removably secure said removable sections in place.

VAN H. BURKHART.
